UNITED STATES PATENT OFFICE

EDWIN G. GODDARD, OF CHICAGO, ILLINOIS, ASSIGNOR OF ONE-HALF TO FLASHTRIC SIGN WORKS, OF CHICAGO, ILLINOIS, A COPARTNERSHIP COMPOSED OF FRED PARKER AND HARRY S. PARKER

ELECTRIC SIGN

Application filed February 20, 1928. Serial No. 255,589.

Due to the fact that electric currents of very high voltage are required to illuminate neon and other gas filled tubes employed for sign characters in electric signs, the practice heretofore has been to use heavily insulated wires or cables for the high voltage current. These wires or cables have been mounted in the body of the sign on insulators relatively close to the metal framework and panels of the sign structure. The insulation about these wires comprises a relatively thick casting of rubber or other insulating material which gives the cables a large outside diameter from one-half to one inch. This brings the outer surface of the cables close to the adjacent metal of the sign body as the cables extend from one insulator to another. The heavy insulation, due to the high tension current passing through the cables, in time deteriorates sufficiently to break down and allows for short-circuiting between the cables and the metal of the sign body producing an arc and setting fire to the insulation. The above is caused directly by the corona or static discharges taking effect, which are known to defeat the purposes of any insulation used for this purpose. In the majority of signs there is sufficient high tension cable used to produce an intense fire which would destroy the entire sign and endanger the building on which the sign is mounted.

In the sign constructions heretofore made there are no positive means for cutting off the current to the signs when they are opened for inspection or repair. Therefore it is possible that a workman repairing the sign is subject to a shock from the high tension cables or transformer on reaching in or entering the live sign. Although a shock may not be fatal in itself, it may cause the workman receiving it to fall from the sign and be badly if not fatally hurt.

In accordance with my invention, I eliminate the shock hazard from the sign structure by providing at each of the inspection doors a switch mechanism which on the door being opened will immediately break the circuit in the sign and render it dead, thereby allowing a workman to reach in or enter the sign without any chance of receiving a shock. The pri-

mary circuit for the sign is in series with all of the door switches, so that when any door is opened the circuit is immediately broken and thus all current supply to the sign cut off and the sign rendered dead. On shutting the doors, the primary circuit is restored so that the sign will be in condition to function. These door switches are used for the complete protection of those who repair and service these signs and should not be misconstrued as the service switches which control the ordinary operation of the signs.

In accordance with my invention, I employ heavily glazed porcelain insulators for mounting the high tension wires in the sign, and by these insulators so space the wires from the metal frame and panels of the sign and other circuits therein that the air spaces between the wires and the metal sign structure are amply sufficient to insulate the high voltage used in these wires, and thus avoid the necessity of any insulating coverings about the wires as heretofore. Thus bare high tension wires may be employed in the sign body with the complete elimination of fire hazard, heretofore mentioned, because of the complete avoidance of all combustible materials.

The invention consists further in the matters hereinafter described and claimed.

In the accompanying drawings—

Fig. 1 is a front view of an electric gas tube sign embodying the features of my invention;

Fig. 2 is a top plan view of the sign;

Fig. 3 is a vertical sectional view taken through the same on line 3—3 of Fig. 2;

Fig. 4 is an enlarged horizontal sectional view taken on line 4—4 of Fig. 3;

Fig. 5 is a vertical sectional view taken on line 5—5 of Fig. 4, with the switch parts in elevation and the door being shown partly open;

Fig. 6 is a vertical sectional view taken on the indirect line 6—6 of Fig. 3;

Fig. 7 is a sectional view taken on line 7—7 of Fig. 6; and

Fig. 8 is a view showing the split flexible disc through which one of the electrodes of the tube extends.

In the drawings, I have shown a double face sign, in which 1, 1 are its front faces, and 2, 2 the several neon or other gas filled tubes which make the letters or characters of the sign. The front faces 1, 1 are usually of metal panels, spaced apart with an intervening wall structure which with the front panels make a hollow sign body or housing to contain the wiring and other mechanism necessary to operate the sign. The wall structure mentioned has top and bottom sections 3, 4 and end sections 5, 5.

In order that access may be had into the sign body at any time, as for the purpose of inspection or repair, the end sections 5, 5 are each provided with an opening 6 normally closed by a door 7, which is located on the outside of the section and preferably hinged at its lower edge so that the door on being opened will swing outwardly and downwardly. A fastener 8 is turnably mounted on each wall 5 above the upper edge of its door for locking and unlocking the door.

Secured to the inside of each door 7 is a porcelain plug 9, which carries a pair of electric contact prongs 10, 10. These enter suitable sockets in a porcelain receptacle 11 carried by a bracket 12 extending across the door opening 6 on the inner side of the wall 5 and bolted or otherwise secured to the wall on opposite sides of the opening, as shown in Fig. 4.

The electrode assemblies 13 for each sign character 2 are at the opposite ends of the glass tubing which forms the character. One of the assemblies is shown in Fig. 6, and there it will be seen that the end portion of the tubing is bent at right-angles to the body of the tubing and is enlarged in the form of a bulb about which is a suitably formed and supported glass receptacle. This assembly extends into the interior of the sign body through the adjacent sign facing 1, the latter having a hole 14 cut therein of a size to permit the assembly to be readily inserted through without chance of breakage and also to take care of an assembly which may be off center or not at right-angles to the main portion of the tube. To close this opening so that it will not appear unsightly on the front face of the sign, I provide a flexible rubber disc 15, which is slit at one side from its outer edge to its center so that the disc may be applied about the tube and hug the same just beyond the bulb assembly, as shown in Fig. 6. The disc has a channel 15^a in its outer edge to receive the edge of the opening 14 and thus support the disc in the opening without the use of bolts or other fasteners. The disc 15 not only closes this opening so that rain, snow, sleet, etc., may not enter the sign body, but also pro-

vides a safety closure preventing a workman from inserting a tool or rod into the sign through the opening to contact with the high tension wires which are in the sign body and connected with the bulbs.

In Fig. 3 will be seen the electrode ends 13 which extend into the sign body from the several tubes 2 on one face of the sign. Located in the sign body and preferably supported on the bottom wall 4 thereof, is a transformer 16 of any preferred construction and having high tension terminals 17, 18. A high tension wire 19 leads from the terminal 17 to one of the electrodes of the first letter "E" of the sign. A high tension wire 20 connects the other electrode of said letter with the adjacent electrode of the second letter "A". A high tension wire 21 connects the other electrode of the letter "A" with the adjacent electrode of the third letter "T", and a high tension wire 22 connects the other electrode of the letter "T" with the other high tension terminal 18 of the transformer, as shown in Fig. 3, thereby completing the high tension or secondary circuit of the sign wiring. The high tension wires 19 to 22 are bare, in that they are not covered with any insulating material. Said wires are supported from the adjacent walls of the sign structure by a number of glazed high tension porcelain insulators 23, 23. These are secured to suitable brackets 24, which are bolted or otherwise tightly secured to a metal part of the sign structure, as shown in Fig. 6. The bare or uncovered high tension wires extend through openings or apertures in the insulators 23 and are looped about them to hold the wires thereon.

In practice, the high tension wires are connected to the stiff terminals 25 of the electrodes at the bulb ends of the tube letters by flexible wire connections 26, as shown in Fig. 6. These wire connections are usually wrapped around and are soldered to the high tension wires at one end and carry clips 27 at their other ends for connection with the terminals 25, as shown.

Leading into the sign body adjacent the transformer 16 are two insulated wires 28, 29, as shown in Fig. 3. The wire 28 is on the live side of the circuit and leads to one of the sockets in the porcelain receptacle 11 at the adjacent door 7. The wire 29 is on the ground side of the circuit and leads to one of the terminals 30 of the transformer 16. An insulated wire 31 connects the other socket of the receptacle 11 with one of the sockets in the receptacle 11 at the other door of the sign. An insulated wire 32 leads from the other socket of the last mentioned receptacle 11 to the terminal 33 of the transformer, as shown in Fig. 3. The wiring just described constitutes the primary circuit of the sign and supplies thereto an electric current from an ordinary commercial lighting circuit. The

voltage of this circuit is stepped up to that required for the tube letters 2 through the transformer 16, as in the operation of signs of the character described.

- 5 When both doors 7 of the sign are closed, the switches 9-11 at each door are closed, and current is supplied to the sign for illuminating it when the service switch in or on the building on which the sign is mounted or 70
- 10 hung is turned on. When either door is opened, the primary circuit is broken, and, as a result no current flows to the sign through either circuit and both circuits are therefore dead. This takes effect automatically on the 75
- 15 opening of either door, and, as the switch members 9-11 on each door are half way up the door, these switch members will be separated before the door is opened far enough to permit access to be had into the sign. Thus, 80
- 20 when a workman opens the sign for repairs or for examining any of the parts within the sign, the current to the sign is immediately cut off and the workman can not receive a shock from even the bare or uncovered 85
- 25 high tension wires in the sign, due to the fact that there is no current flowing through them. The workman may therefore freely work about the sign without any chance of receiving an electric shock. Moreover, as the high 90
- 30 tension wires are bare or uncovered, there is no fire hazard because there is no insulating or other material about the wires to take fire, and moreover the wires are supported far enough away from the metal walls of the 95
- 35 sign body so that no opportunity is afforded for short-circuiting. 100

Large signs are usually made in sections with a multiplicity of letters in each section. The doors for each section would be provided 40 with separable switches 9-11, and these would be wired together so that the circuits of the various sections would be immediately broken on the opening of a door of any section. In the drawings, I have shown a double 45 face sign. My invention is also applicable to single face or other signs.

The details of structure and arrangement of parts described and shown may be variously changed and modified without departing 50 from the spirit and scope of my invention.

I claim as my invention:

1. An electric sign having a casing with a front wall, a gas filled tube mounted on the 55 casing in front of said wall and having electrode assemblies in its ends, said wall having openings to permit the assemblies to be readily and easily inserted therethrough, flexible covers for the openings, said covers 60 being slotted so as to be applied about the tubes adjacent said assemblies and hung about the tubes just beyond the same, and means for holding the covers at the openings.
2. An electric sign of the luminescent gas 65 filled tube type, comprising in combination

a hollow casing forming the body of the sign, one or more gas filled tube characters supported by the casing in position for display thereon, primary and secondary circuits for carrying the commercial lighting and high tension currents, respectively, for the characters, a transformer connecting said circuits for stepping up the low voltage of the primary circuit to the high voltage required for the secondary circuit to illuminate the tube 75 characters in the operation of the sign, said transformer and circuits being located within the casing and exposed for access through either one of a number of openings in the outer wall of the casing, closures, one for 80 each of said openings, and switch means, one for each of said closures, said switch means being connected in series in the primary circuit for automatically breaking both circuits on opening either closure to render the sign 85 inoperative and shock-proof when either closure is open, said switch means automatically re-establishing both circuits to condition the sign for operation on the closing of all closures. 90

3. An electric sign of the luminescent gas filled tube type, comprising in combination a hollow casing forming the body of the sign, one or more gas filled tube characters supported by the casing in position for display thereon, primary and secondary circuits for the tube characters, a transformer through which the circuits are connected for stepping up the low voltage of the primary circuit to the high voltage required for the secondary 95 circuit to illuminate the characters, said transformer and circuits being located in the casing and exposed for access through a closure for said opening, and a switch mechanism for the closure included in the primary 100 circuit for automatically making and breaking both circuits in the closing and opening of the closure to render the sign inoperative and shock-proof when the closure is open and to condition the sign for operation when the closure is closed, the secondary circuit 105 being provided by bare or uncovered wires to avoid inflammable insulating covering and supported far enough from the walls of the sign casing to prevent short circuiting to 110 eliminate fire hazard. 115

In testimony whereof I affix my signature.

EDWIN G. GODDARD.
